UNITED STATES PATENT OFFICE.

EDWARD B. BARNHILL, OF DETROIT, MICHIGAN, ASSIGNEE TO DIAMOND POWER SPECIALTY COMPANY, OF DETROIT, MICHIGAN, A COPARTNERSHIP.

BLOWER FOR BOILERS.

982,459.

Specification of Letters Patent. Patented Jan. 24, 1911.

Application filed February 21, 1910. Serial No. 545,049.

To all whom it may concern:

Be it known that I, EDWARD B. BARNHILL, a citizen of the United States of America, residing at Detroit, in the county of Wayne and State of Michigan, have invented certain new and useful Improvements in Blowers for Boilers, of which the following is a specification, reference being had therein to the accompanying drawings.

10 This invention relates to improvements in blowers for boilers and more particularly to a blower especially adapted for use in blowing tubular boilers of the marine type having several banks of tubes.

15 The object of the invention is to provide a simple and efficient device for the purpose which is so constructed as to adapt it to be mounted within the breeching of a boiler and to be turned therein to direct jets of 20 steam into the several rows of tubes and so constructed that it will operate upon all of the tubes of a boiler when said tubes are arranged in several banks varying in height.

A further object is to so construct the device 25 that it will also operate to blow the tubes of an air heater when such a device is mounted in the usual way upon the boiler breeching.

With these and other objects in view, the invention consists in the construction arrangement and combination of parts as hereinafter more fully described and particularly pointed out in the claims reference being had to the accompanying drawings, in 35 which—

Figure 1 is a sectional end elevation of a boiler showing a blower embodying the invention in place for use thereon; and Fig. 2 is a vertical longitudinal section of the 40 same showing one end of the boiler.

As shown in the drawing 1 represents a marine boiler of the usual construction, having fire tubes 2 which are arranged in banks or groups, groups 3 and 4 being located adjacent to each side of the boiler and group 5 lying between the other groups in the center line of the boiler and extending downward in the usual manner a short distance below the other groups between the fire boxes 6 and 7 and above the central box 8. The boiler is provided with the usual smoke box or breeching 9 and upon the upper side of the breeching is mounted an air heater 10 having vertical smoke flues 11 through 55 which the products of combustion pass on

their way to the stack and around which air is circulated in the usual manner by means (not shown) for inducing a forced draft and supplying the heated air to the fire chamber.

The blower consists of a fixed steam pipe 12 extending horizontally through the lower part of the breeching and a steam supply pipe 13 leading from the top of the boiler or other source of steam under pressure, to one end of the pipe 12, the valve 14 being interposed in the pipe 12 adjacent to its junction with the pipe 13 to shut off steam from the pipe 12. A steam pipe 15 is rotatably mounted in the breeching and extends parallel with the pipe 12 to one end of which pipe it is connected by a short vertical branch 16 and at its opposite end to the supply pipe 13 by a short non-rotative branch 17 within which is a shut off valve 18 to control the flow of steam into said pipe 15 from the pipe 13. Suitable joints 19 are provided to connect the ends of the pipe 15 with the branches 16 and 17 to permit the free rotation of the pipe 15 and prevent the escape of steam from the joint. A laterally extending loop forming a header 20 is secured to the pipe 15 within the breeching by short branches 21 extending laterally from the pipe 15 near each side wall of the breeching and these branches are connected by a pipe extending parallel with the pipe 15 and provided with a series of jet nozzles 22, a nozzle being provided for each vertical row of boiler tubes. When the steam pipe 15 is turned, the header 20 is rotated about said pipe and the nozzles are thus brought successively into position to direct a jet of steam into each of the tubes, and also into the lower ends of the tubes 11 of the heater.

The central bank 5 of tubes being longer than the side banks 3 and 4, it is necessary to provide an extension 23 forming a second header in order to reach the lower horizontal rows of the tubes in the center bank and this pipe 23 is connected to the pipe 20 by short branches 24 extending laterally from the pipe 20 at right angles to the direction of the short branches 21. The pipe 23 is provided with jet nozzles 25 to direct steam into the ends of the tubes.

The pipe 15 with its headers 20 and 23 is turned by means of a worm gear 26 secured to the pipe 15 outside of the breeching and the worm gear is engaged by a worm 27.

upon a shaft 28 mounted horizontally in bearings on the breeching. The shaft 28 is turned by means of a hand wheel 29 or other suitable device.

- 5 Owing to the large number of jet nozzles, if steam should be forced through all of them at one time, a very large supply pipe would be necessary to prevent the steam pressure from being greatly reduced. To
 10 obviate this contingency, a blank coupling 30 forming a division wall is inserted in the pipe 15 at the center line of the boiler and similar blank couplings 31 and 32 are inserted in the pipes 20 and 23 respectively.
 15 Steam entering the pipe 15 through the branch 17 is thus stopped off at the center of the boiler, and if the valve 14 is at the same time closed, steam will be entirely shut off from one half of the jet openings and
 20 one half of the tubes of the boiler will be blown. By closing the valve 18 and opening the valve 14 steam will be admitted to the other end of the blower to blow the other half of the boiler tubes.
 25 In the construction of the blower, common iron pipe may be used and thus a very cheap construction is secured and the particular arrangement provides for blowing all of the tubes in the boiler with a single rotatable
 30 nozzle member.

It is obvious that the use of the header 23 may be dispensed with in boilers of a construction which does not require such an extension in order to reach all of the tubes, 35 and other details of the construction and arrangement of parts may be changed without departing from the spirit of my invention and I therefore do not wish to limit myself to the particular construction shown.

40 Having thus fully described my invention what I claim is:

1. A device of the character described comprising a rotatable steam pipe, a branch pipe extending laterally from the rotatable pipe, a header pipe attached to the free end of the branch pipe and provided with a series of jet openings and means extending from the header pipe and forming a second header carried by the first header to turn therewith 45 when the rotatable pipe is turned.
2. A device of the character described comprising a rotatable pipe, a laterally extending branch on the rotatable pipe, a header on the free end of the branch pipe 55 extending parallel with the rotatable pipe, a branch pipe extending laterally from the header at an angle to the branch pipe connecting the header and the rotatable pipe, and a second header pipe on the end of the branch pipe extending from the first header.
3. A device of the character described

comprising a rotatable steam pipe, means intermediate the ends of said pipe forming a division wall therein, branch pipes extending laterally from the rotatable pipe, a header pipe connecting the free ends of the branch pipes, means intermediate the ends of the header forming a division wall, means for conducting steam into each end of the rotatable pipe, and valves controlling the admission of steam to said ends.

4. A device of the character described comprising a rotatable pipe having means intermediate its ends forming a division wall, a supply pipe connected to one end of the rotatable pipe, a pipe extending parallel with the rotatable pipe and connected to the opposite end thereof, said parallel pipe being connected at the opposite end to the supply pipe, a valve controlling the flow of steam from the supply pipe into the rotatable pipe, a valve controlling the flow of steam from the supply pipe into the parallel pipe, laterally extending branch pipes on the rotatable pipe, a header pipe attached to the free ends of the branch pipes, and means intermediate the ends of the header pipe forming a division wall.

5. The combination with the breeching of a boiler, of a steam pipe extending horizontally through the breeching and rotatively mounted therein, a branch pipe extending laterally from the rotatable pipe, a header on the branch pipe, a worm gear on the rotatable pipe outside of the breeching, a worm in contact with said gear to turn the same, and a valve controlled supply pipe connected to the end of the rotatable pipe.

6. The combination with the breeching of a boiler, of a steam supply pipe, a horizontal pipe connected to the supply pipe and extending through the breeching, a pipe rotatively mounted in the breeching and extending parallel with the horizontal pipe, a branch pipe connecting one end of the rotatable pipe with the supply pipe, a branch pipe connecting the opposite end of the rotatable pipe with the horizontal pipe, means on the rotatable pipe outside of the breeching for rotating said pipe, laterally extending branch pipes upon the rotatable pipe within the breeching, a header connected to the free ends of said branch pipes, and means within the rotatable pipe and header pipe intermediate the ends thereof forming division walls.

In testimony whereof I affix my signature in presence of two witnesses.

EDWARD B. BARNHILL.
